UNITED STATES PATENT OFFICE

2,426,403

FOOTWEAR

Peter H. Margulis, New York, N. Y.

Application January 24, 1945, Serial No. 574,253

6 Claims. (Cl. 36—50)

1

This invention relates to footwear in which term it is intended to include boots, shoes, oxfords, and other footwear for men, women and children.

The invention has for its salient object to so construct an article of footwear that it can be readily adjusted to comfortably fit the foot and leg of the wearer and, moreover, to readily fit various measurements of insteps, ankles and calves.

Another object of the invention is to provide an article of the character described so constructed and arranged that it will present a neat, form fitting and attractive appearance on the wearer.

Another object of the invention is to provide an article of footwear so constructed that it can be easily and quickly put on and taken off.

Another object of the invention is to provide an article of footwear of the character described so constructed that it will be adapted for many uses, such as business, dress, or work purposes, and also so constructed that it is particularly adapted for use in the armed services.

Further objects of the invention will appear from the following specification taken in connection with the drawings which form a part of this application, and in which

Fig. 1 is a perspective view of a boot embodying the features of the invention;

Fig. 2 is a perspective view of two connected blanks used in forming the boot shown in Fig. 1;

Fig. 3 is an elevation showing another blank used in making the boot shown in Fig. 1;

Fig. 4 is a perspective view showing a slight modification of the construction shown in Fig. 1 and also illustrating the boot as open for the reception of the foot of the wearer; and

Fig. 5 is a perspective view illustrating a different type of boot or shoe embodying the invention and particularly adapted for the armed services.

In the particular embodiment of the invention illustrated in Figs. 1 to 4 inclusive, there is shown a boot particularly adapted for hunting, riding, or general outdoor work or recreation. This boot may be constructed of various materials but is preferably made of leather or, if desired, of rubber, and comprises a vamp V, counter C, and the upper U.

As shown particularly in Fig. 2, a portion of the upper U comprises two parts, a flap 10 and a complementary section 11, which are connected together at the back 12 and may, if desired, be reinforced by a strip 13.

The flap or portion 10 is provided with concave portions 14 and 15 and with rounded projecting portions 16 and 17. The flap 10 also has a notch 18 at the upper end of the portion 19 which forms a part of the vamp V.

2

The lower portion of section 11 of the upper has a projection 20 which forms a notch 21 having a substantially vertical edge 22.

The vamp V is formed partially by a portion 5 19 of the lower end of the upper U and partially by a corresponding and complementary portion 25 of a section 26. The upper end portion 27 of section 26 is secured by stitching or cementing to the lower edge portion 28 of the flap 10 and is also secured along an edge portion 29 to the vertical edge 22 of the part 11. The edge 23 of the section 26 is also stitched or otherwise secured to the edge 24 of the part 19. The lower edge of the bottom end of the flap 10 and upper edge of the part 26 form a rounded projecting portion 33 corresponding to portions 16 and 17.

Particular attention is directed to a forwardly and downwardly inclined notch 30 formed in the section 26 at the instep covering portion or entrance to the shoe or boot. This notch is designed for the purpose of providing a wide opening at the instep covering portion when the flap 10 is folded back, as shown in Fig. 4, to facilitate the insertion of the foot in the shoe or boot. Moreover, this construction provides a neat adjustment on the ankle and instep where the foot flexes.

The notch 30 in the section 26 may, if desired, be reinforced by stitching, as shown at 32, or by cementing. The section or flap 10 and connected part 26, which forms a unitary flap, are secured to the part 11 by means of straps and buckles.

35 As shown in Figs. 1 and 4, the heel 35 and sole 36 are secured to the boot in any desired well known manner.

In Fig. 1 there is shown a strap 40 which is secured to the back of the boot or on the counter 40 C adjacent the heel and encircles the instep and is carried around to the back of the boot and through opening 41 in the back strip 13. A buckle 42 is engaged by a strap 43 secured to the flap 10, thus tightening the boot and closing the flap to cause a neat and attractive fit. It will be noted that the strap 40 passes over the flap 44 above the notch 30 and insures the closing of this flap.

The projecting portions 16 and 17 have secured thereto straps 45 and 46 which coact with buckles 47 and 48 to close the flap 10 and close the boot to fit neatly and closely around the calf of the wearer.

In Fig. 4 three straps 50, 51 and 52 are secured 55 to projecting portions 53, 54 and 55 of the flap and these straps coact with buckles 56, 57 and 58 to close the flap and cause the boot to fit closely and neatly around the leg of the wearer.

Fig. 5 illustrates a slightly modified form of 60 construction in that the invention is applied to

a low boot instead of a high boot, as in the preceding figures. In this construction the notch 63 corresponds to and performs the function of the notch 30 illustrated in the preceding figures. Furthermore, the strap 61 encircles the instep in the manner similar to the strap 40 and is provided with a buckle 62 which is engaged by a strap 63 secured to the flap 64.

It will be evident from the foregoing description that because of a wide opening permitted by the notch at the instep covering portion, the boot can be very easily put on and taken off and, furthermore, because of the particular strap securing means, the boot can be readily adjusted to fit various measurements of insteps, ankles and calves to provide a neat, form fitting appearance.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. An article of footwear including an upper adapted to enclose the instep of the wearer, said upper including a flap extending from the instep covering portion of the article to its top and adapted to overlie the other side of the upper, the lower end of the flap and adjacent portion of the article being separated from each other by a relatively narrow elongated notch and extending forwardly and downwardly, one wall of the notch being anchored and the other wall of the flap and movable relative to the anchored wall of the notch.

2. An article of footwear including an upper adapted to enclose the instep and at least a portion of the ankle of the wearer, said upper including a flap extending from the instep covering portion of the article to its top and adapted to overlie the other side of the upper, the edge of the flap being undulated to provide spaced projections, the lower end of the flap and adjacent portion of the article being separated from each other by a relatively narrow elongated notch below the lowest projection and extending forwardly and downwardly, one wall of the notch being anchored and the other wall of the notch constituting the free edge of the flap and movable relative to the anchored wall of the notch.

3. An article of footwear including an upper adapted to enclose the instep and at least a portion of the ankle of the wearer, said upper including a flap extending from the instep covering portion of the article to its top and adapted to overlie the other side of the upper, the edge of the flap being undulated to provide spaced projections, the lower end of the flap and adjacent portion of the article being separated from each other by a relatively narrow elongated notch below the lowest projection and extending forwardly and downwardly, one wall of the notch being anchored and the other wall of the notch constituting the free edge of the flap and movable relative to the anchored wall of the notch, and means including a strap to anchor the flap extending across the projection of the flap adjacent said notch.

4. An article of footwear including an upper adapted to enclose the instep and at least a portion of the ankle of the wearer, said upper includ-

ing a flap extending from the instep covering portion of the article to its top and adapted to overlie the other side of the upper, the edge of the flap being undulated to provide spaced projections, the lower end of the flap and adjacent portion of the article being separated from each other by a relatively narrow elongated notch below the lowest projection and extending forwardly and downwardly, one wall of the notch being anchored and the other wall of the notch constituting the free edge of the flap and movable relative to the anchored wall of the notch, and means for retaining the undulated edge of the flap in overlying closed relation to the other side of the upper including a series of straps, all of said straps respectively passing over said projections and being unattached thereto whereby limited movement of the flap is permitted when the footwear is in use.

5. A form fitting article of footwear including an upper to enclose the instep and at least a portion of the ankle of the wearer, a flap secured to one side of the upper and having an undulating edge extending from the throat of the article to its top and adapted to overlap the other side along a side of the ankle, straps secured to said flap and upper and adapted to encircle the ankle of the wearer and extend across the instep, and means to maintain said straps across the projections on the said undulating edge whereby in tightening the straps the stress is applied across said projections and across the instep to maintain the flap in close non-bulging contact with the other side of the upper and to neatly conform the upper to the foot and ankle of the wearer.

6. In a form fitting adjustable article of footwear, an upper, a flap having an undulating side edge on one side of the upper to overlie a portion of the opposite side of the upper, the lower edge of said flap extending along and being secured to the top edge of the vamp in permanently overlapping relation to the lower portion of said opposite side to bias said flap and undulating edge toward said opposite side of the upper, whereby said flap and undulating edge automatically fall rearwardly upon said opposite side of the upper, a strap secured to said opposite side of the upper adjacent its bottom, a second strap secured to the flap adjacent its top, and means on said strap for joining their free ends with the said straps disposed across projections on said undulating edge when they encircle said article to prevent the flap from bulging.

PETER H. MARGULIS.
